UNITED STATES PATENT OFFICE

160,294

FINGER RING

Oscar E. Bass, Hendersonville, N. C.

Application July 31, 1950, Serial No. 11,506

Term of patent 7 years

(Cl. D45—10)

To all whom it may concern:

Be it known that I, Oscar Earle Bass, a citizen of the United States of America, residing at Hendersonville, North Carolina, have invented a new, original, and ornamental Design for a Finger Ring, of which the following is a specification, reference being had to the accompanying drawing, forming a part thereof.

In the drawing:

Fig. 1 is a top plan view of a finger ring, embodying my new design;

Fig. 2 is a side elevational view thereof; and

Fig. 3 is an opposite side elevational view thereof.

I claim:

The ornamental design for a finger ring, substantially as shown.

OSCAR E. BASS.
